UNITED STATES PATENT OFFICE.

FRED CRAWFORD, OF PROSSER, WASHINGTON.

CUTTING APPARATUS FOR MOWERS.

1,239,570.

Specification of Letters Patent. Patented Sept. 11, 1917.

Application filed March 20, 1917. Serial No. 156,148.

To all whom it may concern:

Be it known that I, FRED CRAWFORD, a citizen of the United States, residing at Prosser, in the county of Benton and State 5 of Washington, have invented certain new and useful Improvements in Cutting Apparatus for Mowers, of which the following is a specification.

This invention relates to cutting apparatus for mowing machines and harvesters, and has for its object the provision of a cutting apparatus in which the wear upon the cutter and the finger bar will be minimized and made even throughout the extent 15 of the parts and also to provide novel means for securing the guard fingers to the finger bar. A further object of the invention is to provide a finger bar which will be light and strong and also to produce a construction 20 which will permit ready removal of a broken guard finger and the substitution of a new guard finger therefor.

The invention is fully illustrated in the accompanying drawings, in which:

25 Figure 1 is a plan view of a portion of a cutting apparatus constructed in accordance with my invention, parts being broken away;

30 Fig. 2 is a transverse section on the line 2—2 of Fig. 1;

Fig. 3 is a section on the line 3—3 of Fig. 1;

35 Fig. 4 is a detail perspective view of a guard finger and the anchor bolt by which it is held in the finger bar.

In carrying out my invention, I employ a finger bar 1 which is preferably composed of upper and lower webs disposed in parallel relation and connected by a vertical web 40 2 at their rear ends and free at their front ends. At intervals in the rear web 2, I provide openings 3 through which the anchor bolts for the guard fingers are passed. The guard fingers are provided with the usual 45 tapered bodies 4 which when in operative position project forwardly from the finger bar and are recessed to receive stationary knives 5 which are secured to the guard fingers by countersunk screws or rivets in the 50 usual manner and have their rear ends seated in the recesses in the upper sides of the guard finger bodies, as shown at 6 in Fig. 4. The rear portions of the guard fingers are 55 extended laterally to provide shoulders 7 upon which the reciprocating knives may slide and also to provide vertical shoulders or

ledges 8 which form the front guides for the cutter bar 9. In rear of the vertical shoulder or ledge 8, the surface of the guard finger is smooth so as to engage the under 60 surface of the upper web of the finger bar 1, a transverse groove 10 being formed in the rear portion 11 of the guard finger to contain lubricant or, if so desired, rollers or balls which aid in supporting the cutter bar 9 and 65 reducing the frictional resistance to its reciprocation. It will be readily noted that the rear portion 11 of the guard finger forms an angular tongue which is adapted to fit snugly between the upper and lower webs 70 of the finger bar and on the under side of said tongue is a vertical shoulder 12 which is adapted to bear against the front edge of the lower edge of the finger bar and thereby limit the insertion of the guard finger into 75 the finger bar. It will also be noted that the under surface of the guard finger is flush with the under surface of the finger bar so that no obstruction to the forward travel of the apparatus is presented. The tongue 80 11 is bifurcated, as shown at 13, to receive the stem or shank 14 of the anchor bolt by which the guard finger is held in the finger bar. The vertical walls of the bifurcations are flat, as clearly shown in Fig. 4, and said 85 bifurcation opens into an enlarged angular recess 15 which receives the head 16 of the anchor bolt. It will be readily noted that the forward and side walls of this recess 15 are flat-faced to form an angular engagement 90 with the corresponding surfaces of the head 16 and the rear walls of said recess or chamber are inclined downwardly and forwardly so as to engage the downwardly and forwardly inclined side portions 95 17 of the head 16, the vertical dimension or thickness of the head 16 being the same as the vertical dimension of the tongue 11 so that the upper and lower surfaces of the head and shank will lie flush with the upper and lower surfaces of the tongue and will fit snugly in between the upper and lower webs of the finger bar and thereby be prevented from vertical movement relative 100 to the finger bar. The rear portion of the stem of the anchoring bolt is cylindrical, as shown at 18, to project through the opening 3 in the finger bar, the extremity of said cylindrical portion being threaded to receive a nut 19 by which the parts are firmly 110 clamped together. It will be readily understood that by turning the nut 19 home

against the vertical web of the finger bar a pull is exerted through the anchor bolt upon the tongue 11 of the guard finger so that the same is drawn within the finger bar 5 until the shoulder 12 engages the front edge of the finger bar, whereupon the parts will be firmly clamped against all relative movement. It will also be readily noted that by removing the nut 19, the guard finger and the anchor bolt may be drawn forward from 10 within the finger bar without disturbing the other parts of the apparatus and, therefore, a broken guard finger may be easily removed and a new guard finger substituted therefor. Moreover, the same anchor bolt may 15 be used repeatedly for successive guard fingers inasmuch as it is not a part of the guard finger but may be easily lifted out of its engagement with the same after the parts have been removed from the finger bar.

Between the guard fingers, I provide spacing blocks 20 which have rear angular portions fitting closely between the upper and lower webs of the finger bar and secured 25 rigidly therein by bolts 21 inserted therethrough, as clearly shown in Fig. 2. These spacing blocks have their forward edges curved out upwardly, as shown at 22 whereby they will ride readily over the grass 30 without causing the apparatus to clog and their extreme under surfaces are disposed flush with the under surfaces of the guard fingers, as shown in Fig. 2. The spacing blocks are also provided with transverse 35 shoulders 23 on their under sides which fit against the forward edge of the finger bar and in their upper surfaces are transverse grooves 24 which align with the transverse grooves 10 in the upper surface of the guard 40 fingers. The spacing blocks are also constructed with horizontal shoulders 25 and vertical shoulders 26 which form ways or guides for the cutting bar 9 so that the said bar will be positively supported throughout 45 the apparatus and will be caused to run true and evenly when in operation. The cutter bar 9 is rectangular in cross section so as to properly engage the ways or guides in the guard fingers and the spacing blocks, and 50 the knives 27 are secured at their inner ends at the upper side of said bar in the usual manner.

A wear plate 28 is secured upon the upper side of the finger bar by the bolts 21 and 55 this wear plate is provided at its front edge with a depending lip 29 which fits against the front edge of the upper web of the finger bar and fills the space between said edge and the rear edge of the cutter bar 9 thereby 60 furnishing a guide for the cutter bar and presenting a continuous uninterrupted surface against which said bar may swing and which receives the thrust of the same due to the resistance of the grain to the operation 65 of the knives. The wear upon the cut-

ter bar is, consequently, uniform throughout its length and may be taken up by adjusting the wear plate 28 forwardly, as will be readily understood. To permit said adjustment, the wear plate is provided with slots 30 70 through which the bolts 21 pass. A keeper plate 31 is also secured upon the finger bar by the bolts 21 and this keeper plate projects forwardly over the cutters and has its front edge extended slightly into the recess in the guard finger through which the cutters play, the intermediate portion of the keeper plate being arranged, as shown at 32, whereby it will be raised out of contact with the inner ends of the movable knives and thereby minimize the frictional resistance to the operation of the same. This keeper plate serves to hold the movable knives close to the stationary knives so that the proper cutting action will be attained and also 80 serves to prevent the dropping grain catching upon the knives and being worked into the spaces in the guard fingers provided for the recess so that the cutting apparatus will not be easily clogged and the machine may 90 be operated continuously without any perceptible increase in the draft.

The operation and advantages of my improved apparatus are thought to be evident from the foregoing description taken in 95 connection with the accompanying drawings and further detail mention of the same is deemed unnecessary.

Having thus described the invention, what is claimed as new is:

1. In a cutting apparatus, the combination of a finger bar, a guard finger having its rear portion inserted within and housed by the finger bar, and an anchor bolt having a wedging engagement with the rear portion 105 of the guard finger and housed by the same and the finger bar and extending through and secured in the rear side of the finger bar.

2. In a cutting apparatus, the combination of a finger bar, a guard finger having a flat tongue at its inner end fitting within the finger bar and having said tongue constructed with an angular vertical opening and a bifurcation leading from said opening through the rear end of said tongue, the rear end walls of said recess at the sides of the bifurcation being inclined, and an anchor bolt having an angular head fitting within said recess and provided with rear 115 inclined surfaces engaging the rear inclined walls of the same, and a shank extending through the said bifurcation and secured in the finger bar.

3. In a cutting apparatus, the combination of a finger bar, a guard finger provided on its under side with a transverse shoulder adapted to fit against the front edge of the finger bar and having a tongue extending 125 into the finger bar, an anchor bolt having a 130

wedging engagement with said tongue and held against vertical movement by the finger bar and provided with a threaded stem extending through the rear side of the finger bar, and a nut mounted on said stem and bearing against the rear side of the finger bar.

4. In a cutting apparatus, the combination of a finger bar, a plurality of guard fingers secured in the finger bar, a plurality of spacing blocks secured in the finger bar between the guard fingers, the front edges of the spacing blocks being convex and the under sides of the spacing blocks and the

guard fingers being flush with the under 15 surface of the finger bar, the under surfaces of the spacing blocks and the guard fingers being provided with transverse shoulders to bear against the transverse shoulder of the finger bar and the upper 20 sides of the spacing blocks and the guard fingers being constructed with alined transverse grooves, a cutter bar slidably seated in the guard fingers and the spacing blocks, and cutters carried by said cutter bar. 25

In testimony whereof I affix my signature.

FRED CRAWFORD. [L.S.]
